UNITED STATES PATENT OFFICE.

HERMAN BIEDER, OF CLEVELAND, OHIO.

LAMP HOLDER.

Application filed November 30, 1921. Serial No. 518,782.

To all whom it may concern:

Be it known that I, HERMAN BIEDER, a citizen of the United States, resident of Cleveland, county of Cuyahoga, and State 5 of Ohio, have invented new and useful Improvements in Lamp Holders, of which the following is a specification, the principle of the invention being herein explained and the best mode in which I have contemplated 10 applying that principle, so as to distinguish it from other inventions.

My invention relates to lamp holders and particularly to a device of this character designed for holding electric lamp bulbs on extension cords. It is the object of my invention to provide a holder of this character capable of being quickly attached to any available support whereby the light may be readily placed in the position most convenient for 20 the user. A further object is to provide a holder of this character which can be economically manufactured, which is neat in appearance, and which is of durable construction. Other objects will be apparent 25 from the following description together with the annexed drawings.

The present application is a continuation in part of my prior copending application Serial No. 318,736, filed Aug. 30, 1919.

30 The annexed drawings and the following description set forth in detail certain means embodying my invention, the disclosed means, however, constituting but one of the various mechanical forms in which the principle of the invention may be applied.

In said annexed drawings:

Fig. 1 is a side elevation showing my improved holder used as a supporting stand for the lamp.

40 Fig. 2 is a side elevation showing another position in which the holder may be used as a supporting stand.

Fig. 3 is a side elevation showing in full lines, the holder clamped to a ledge, shelf, 45 beam or other flat support and in dotted lines the holder clamped to the extension cord.

Fig. 4 is a plan view of the holder viewed as indicated by the line IV—IV of Fig. 5.

50 Fig. 5 is a side elevation of the holder showing the clamping jaws in full open position.

Fig. 6 is a plan view of the holder, viewed as indicated by the line VI—VI of Fig. 5.

55 Fig. 7 is a detail plan view of the actuating arm to which the lamp retainer is se-

cured, viewed as indicated by the line VII—VII of Fig. 5.

Fig. 8 is a sectional detail view through the lamp socket retaining cup, taken on line VIII—VIII of Fig. 5.

Fig. 9 is an end view of one of the clamping arms, viewed as indicated by the line IX—IX of Fig. 5.

Fig. 10 is a side elevation showing a small 65 automobile lamp held in place by a special attachment.

Fig. 11 is a section on line XI—XI of Fig. 10.

Referring to the annexed drawings, my 70 improved holder is designed to support a lamp 1 seated in a socket 2 attached to the end of an extension cord 3. As shown in Figs. 1, 2 and 3 the holder is designed to be used as a supporting stand or to be clamped 75 to supports of various kinds. The clamping portion of the holder comprises a pair of sheet metal body members 4 and 5, provided with inturned lugs 6 which receive a pintle 7 by means of which the members 4 and 80 5 are hingedly connected, said body members having clamping jaw portions 8 and 9 projecting forwardly from the hinge connection and actuating arm portions 10 and 11 extending rearwardly from the hinge 85 connections and angularly disposed with respect to the clamping jaw portions; together with wire loop extensions 12 and 13 secured to the clamping jaw portions. Mounted on the pintle 7 is a coil spring 14 90 the opposite ends of which bear upon the arm portions 10 and 11 of the clamping members, and normally hold the jaws in closed position and the actuating arms in extended position as shown in Figs. 1 and 2. 95

The jaw portions 8 and 9 are provided at the edges thereof at their outer ends with rolled over edges forming sockets 15 which receive the ends of the U shaped wire clamp extensions 12 and 13. The extensions 12 and 100 13 are bent in opposite directions adjacent the body portions 8 and 9 and the extension 12 is narrower and shorter than the extension 13 so as to be freely movable within the extension 13. The clamping jaw portions 105 8 and 9 of the body members are provided adjacent the lips 6 with inner registering grooves 16 adapted to receive the extension cord 3 when it is desired to hang the holder on the extension cord. The wire 110 extension members 12 and 13 have square outer end portions which are bent inwardly

as indicated at 17 in Fig. 9 whereby a four point contact is provided in clamping to flat objects such as shown in Fig. 3. For reinforcing the sheet metal body members 4 and 5 at the bend over the hinge, longitudinally disposed ribs 18 extending across the bend are stamped in the body of the plates. The marginal edges of the arm portions 10 and 11 are reinforced by rolled over 10 beads 19.

The arm 10 is provided with a keyhole slot 20. Secured to the arm 10 is a cup shaped socket retaining member 21. The member 21 has a central opening in the bottom surface 15 rounded by a marginal flange 22 fitting within the enlarged portion of the keyhole slot 20 and turned over against the inner face of the plate to secure the retaining member in place on the arm. The cup 21 has a slot 23 registering with the slot 20 of the arm to permit the extension cord 3 to freely enter the cup when the socket 2 is inserted therein. The cup member 21 is constructed of resilient metal and is provided 25 with slots 24 extending downwardly from the upper edge to permit the walls of the cup to spring outwardly sufficiently to permit the socket 2 to be pressed into the cup. The outer edge of the cup 21 has an inturned 30 retaining flange 25 adapted to spring over the outer edge of the peripheral ribs 26 on the socket 2. As shown in Figs. 1, 2 and 3, the switch button 27 of the socket 2 is clear of the cup 21 so that the socket can be freely 35 rotated therein. This is advantageous in that the switch button is always readily accessible and where a shade or reflector is used with the bulb the light can be directed in the desired direction.

40 The arm 11 is provided with a keyhole slot 28 corresponding exactly to the slot 20 in the arm 10. Rotatably fitting in the enlarged portion of the keyhole slot 28 is an eyelet ring 29 which has a cut away portion 45 adapted to register with the narrow entrance portion of the slot as shown in Fig. 4. By rotating the ring 29 the enlarged portion of the slot 28 can be closed to retain the cord 3 therein as indicated in dotted lines 50 in Figs. 4 and 8. By reason of this arrangement the cord cannot interfere with the operation of the clamp, the cord is not bent adjacent the socket on operation of the clamp and consequently there is no danger of 55 breaking the wires in the cord at this point.

As shown in Figs. 4 and 6 the arms 10 and 11 and the wire extension 13 have wide square ends and are adapted to serve as supporting legs for the holder as shown in Figs. 60 1 and 2.

The extensions 12 and 13 are adapted to firmly engage any relatively flat object and the jaw portions 8 and 9 together with the extensions 12 and 13 are adapted to clamp 65 a bar, pipe, rod or the like.

In Figs. 10 and 11 I have shown an attachment by means of which small light sockets such as used in automobiles may be secured in the retaining cup 21. The small socket 30 is held in place in the cup 21 by 70 means of a cap 31 which is provided with a central aperture to receive the end of the socket 30 and a cylindrical flange 32 adapted to be slipped over the slotted cylindrical wall of the cup 21. The spring pressure of 75 the wall portions of the cup 21 between the slots 24 serves to frictionally hold the retaining cap 31 in position.

What I claim is:

1. A lamp holder of the character described, comprising a pair of pivotally connected sheet metal body members formed to provide forwardly extending clamping jaws and rearwardly extending actuating arms, said arms comprising flat plates angularly disposed with respect to said clamping jaws; and a lamp socket supporting member carried by one of said plates, both of said plates being slotted from their outer ends to receive the lamp cord. 90

2. A lamp holder of the character described, comprising a pair of pivotally connected sheet metal body members formed to provide forwardly extending clamping jaws and rearwardly extending actuating arms, 95 said arms comprising flat plates angularly disposed with respect to said clamping jaws; a spring for normally holding said clamping jaws in closed position; and a lamp socket receiving member mounted upon the outside of one of said plates said member being slotted to receive the lamp cord, said plate upon which said member is mounted having a slot leading from the end thereof to the slot in said receiving member and the other plate having a cord receiving slot in alinement with the slot in said first mentioned plate. 100

3. A lamp holder of the character described, comprising a pair of pivotally connected sheet metal body members formed to provide a pair of forwardly extending clamping jaws and rearwardly extending actuating arms; a spring for normally holding said jaws in clamping position; a lamp socket retaining member secured to one of said arms, said arm and said retaining member being slotted to receive the lamp cord, and the other arm being provided with a corresponding cord receiving slot; and means carried by the last mentioned arm for retaining said cord in the slot. 110

4. A lamp holder of the character described, comprising a pair of body members each formed with a forwardly projecting clamping portion and a rearwardly projecting actuating arm portion angularly disposed with respect to said clamping portion; a hinge connection between said body members adjacent the angles between said jaw 120 125 members. 130

and arm portions; a spring for normally holding said jaws in closed position and said arms in extended position; and a lamp retaining member mounted on one of said arms; said arms being relatively wide at their outer ends and of equal length at their outer edges whereby said arms are adapted to form supporting legs for said holder.

5. A lamp holder comprising, a pair of pivoted members formed to provide clamping jaws on one side of the pivot and actuating arms on the opposite side of said pivot, said clamping jaws having end portions bent in opposite directions, one of said end portions having an opening through which the end portion of the other jaw passes, said arms being angularly disposed with respect to said clamping jaws; a spring for normally

holding said jaws in closed position and said actuating arms in extended position; and a lamp retaining member mounted on one of said actuating arms; said actuating arms and one of said jaws have square ends whereby they may form supporting legs for said holder.

25

6. A lamp holder comprising a clamp, a lamp socket retaining cup carried by said clamp, and a lamp socket retaining cap adapted to detachably fit over the open outer end of said cup and having a central aperture adapted to receive the outer end of the lamp socket.

Signed by me this 29th day of October, 1921.

HERMAN BIEDER.
